ARTHUR H. PETERS, OF FORT WAYNE, INDIANA, ASSIGNOR TO HORTON MANUFACTURING COMPANY, A CORPORATION OF INDIANA.

SAFETY DEVICE FOR WRINGERS.

1,238,938.

Specification of Letters Patent. Patented Sept. 4, 1917.

Application filed March 20, 1916. Serial No. 95,278.

To all whom it may concern:

Be it known that I, ARTHUR H. PETERS, a citizen of the United States of America, and resident of Fort Wayne, in the county of Allen and State of Indiana, have invented certain new and useful Improvements in Safety Devices for Wringers, of which the following is a specification.

This invention relates to improvements in safety devices for wringers, especially of that class employed in conjunction with power-driven washing machines. The object of the improvements are: First, to construct the device so that its operation may 10 be stopped instantly at any stage in order to avert impending accident; and second, to afford a simply constructed device by means of which the apparatus may be readily readjusted to operating position after having 15 been thrown out of position.

The objects of the improvements are accomplished by the construction illustrated in the accompanying drawings in which:

Figure 1 is a plan view of the supporting bracket, operating lever and springs for holding same in normal position;

Fig. 2 is a bottom plan of the same and including also the securing yoke and adjusting sleeve;

Fig. 3 is a side elevation of the operating member; and

Fig. 4 is a front elevation of a wringer with the device applied thereto with a portion of the latter in section.

Similar characters of reference indicate corresponding parts throughout the several views and referring now to the same:

(1) is a wringer having standards (2) at the sides thereof in which are mounted 40 the wringer rollers (3) which are arranged to be compressed together in the usual manner, by means of pressure applied by the spring (4) that bears at its respective ends upon the bearings (5).

A bracket (6) is secured at its respective ends in the top of the standards (2) and has mounted loosely therein an adjusting sleeve (7). A stud (8) in fixed relation with the spring (4) at the center thereof has

screw-threaded relation with the sleeve (7) 50 so that as the latter is turned in one direction or the other the spring will become impressed more or less upon the bearings (5) which has the effect of holding the rollers together with force accordingly. 55

An annular recess (9) is made in the sleeve at a point above the bracket (6) and a latch (10) extending in a slot (11) in the bracket is secured upon a pivot (12). A projection (13) on the upper end of the latch (10) extends normally into the groove and engages the shoulder (14) on the sleeve so as to hold the sleeve from rising. A spring (15) arranged within the bracket acts against the latch at a point beneath the pivot (12) so that the projection (13) tends to bear against the sleeve and enter the recess when alined therewith. A tubular extension (16) is fixed in the lower side of the bracket through which the sleeve (7) 70 extends in bearing relation, and upon the extending portion of the tube is mounted the operating member which is comprised of a horizontal bar (17) having at each of its ends a pendant handle (18). The ends 75 of the bar (17) project oppositely from the corresponding sides of the bracket (6) so that the handles depending therefrom are normally positioned adjacent the opposite sides of the uppermost roller (3) of the 80 wringer. The operating member is held upon the extension (16) loosely, so that it may be oscillated thereupon, by means of a yoke (19), a cap-screw (20) serving to secure the yoke to the underside of the 85 bracket. A pair of tension springs (21), each secured at one end to a screw (22) on the bracket, and having their respective opposite ends secured to the corresponding opposite ends of the bar (17), serve to yieldingly hold the operating member in normal position with the bar extending at right angles to the bracket. From one side of the bar (17) extends a lug (23) that is adapted to block inward swinging movement of the 95 lower end of the latch (10), when the operating member is in normal position and also to move out of the path of the latch

when the operating member is turned upon the extension in either direction. Thus the latch will be normally locked in engagement with the shoulder (14) of the sleeve 5 and prevent its rising, but when the position of the operating member is shifted the sleeve may be released from the detention 10 of the latch when pressed upwardly by the action of the spring (4), the latch being free to swing upon its pivot when not obstructed by the lug. The latch (10) being pivoted at a point at one side of the sleeve readily slips from its holding engagement 15 with the shoulder (14) on the sleeve when the latter bears upwardly and when the latch is not hindered by the lug on the operating member.

In the operation of the invention the rollers (3) are held together with more or less 20 pressure exerted by the spring (4) accordingly as the sleeve is turned by manipulating its hand-wheel (24), and as the rolls are revolved in the customary manner, in the event of an impending accident, the operator 25 may release the spring pressure upon the rollers by simply shoving the operating member to one side or the other which has the effect of throwing the lug from the path of the latch so that the sleeve slips from its 30 detained position. This facility is especially of advantage where the rollers are operated by power with a remote control, inasmuch as the rollers may be instantly released from pressure of the spring by the 35 disengagement of the latch from the sleeve which takes place when the operating member is slightly turned laterally in either direction by manipulation from either side of the wringer. Thus, should the operator 40 accidentally allow his hand to be drawn between the rollers, it is only necessary upon his part to escape injury, to strike one or the other of the handles (18) which will effect the release of the pressure between 45 the rollers. After the sleeve has been thus released, in order to restore pressure to the rollers, the sleeve is turned downwardly upon the threaded stud (8) until the latch again engages in the recess, the swinging of 50 the latch having also the effect of disengaging the lug (23) so as to permit the operating member to re-assume its normal position. The desired amount of pressure 55 may then be applied to the spring (4) by turning the sleeve in the opposite direction to the extent required.

What I claim is:—

1. In apparatus of the class described, in combination with a wringer having a frame 60 and spring pressed rollers mounted therein, a bracket mounted on the frame, a threaded stud fixed upon the spring of the wringer, a recessed adjusting sleeve ex-

tending through the bracket and having threaded relation with the stud, a spring 65 pressed latch adapted to engage the sleeve in the recess thereof, and an operating member adapted to normally hold the latch in engaging position.

2. In apparatus of the class described, the combination of a wringer having a frame and rollers mounted therein, a spring acting against the bearings of one of the rollers having a threaded stud fixed thereupon, a bracket mounted in the frame above the 75 spring, a recessed adjusting sleeve extending through the bracket and having threaded relation with the stud, a spring pressed latch pivoted in the bracket engaging the sleeve in the recess thereof, and an operating member in pivotal relation with the bracket and adapted to normally hold the latch in engaging position.

3. In apparatus of the class described, a frame having a bracket fixed in the top 85 thereof, a pair of wringer rollers mounted in the frame, a spring having bearing relation to hold the rollers together and having a threaded stud fixed thereon, a recessed sleeve having threaded relation with the 90 stud and extending movably through the bracket, a latch pivoted in the bracket adapted to engage the sleeve in the recess thereof, and an operating member adapted to engage and hold the latch in normal position.

4. In apparatus of the class described, a pair of wringer rollers, a spring for compressing the rollers together and having a threaded stud in connection therewith, a 100 sleeve engaging the stud, a pivoted latch adapted to engage and hold the sleeve in operating position; and an operating member against which the latch bears and is thereby held in engaging relation with the 105 sleeve and which is adapted to release the latch from engagement therewith when actuated.

5. In apparatus of the class described, a wringer proper including a spring for compressing the rollers thereof, a threaded sleeve engaging the stud, a latch for engaging the sleeve adapted to hold the latter in operative position, an operating member for normally holding the latch into engagement 115 with the sleeve, and springs for holding the operating member into engaging relation with the latch.

6. In apparatus of the class described, the combination with a wringer proper including a spring for compressing the rollers thereof together, a threaded stud on the spring, a bracket having a pendant tubular extension, a sleeve having threaded relation with the stud and extending movably 120 through the bracket and pendant extension 125

thereof, a spring pressed latch pivoted in the bracket and adapted to normally engage the sleeve, an operating member loosely mounted upon the extension and having a lug projecting therefrom adapted to engage and hold the latch in connected relation with the sleeve, springs for normally holding the operating member in engaging po-

sition, and a yoke for retaining the operating member upon the extension.

In testimony whereof I affix my signature, in presence of two witnesses.

ARTHUR H. PETERS.
